DESCRIPTION

U.S. PATENT DOCUMENTS

FIG. 1 is a front perspective view of a power tool battery according to an embodiment of the present invention.

2,876,273 A *	3/1959	Hall	429/100
4,050,003 A	9/1977	Owings et al.	
4,410,846 A	10/1983	Gerber et al.	
4,522,270 A	6/1985	Kishi	
4,626,765 A	12/1986	Tanaka	
4,638,237 A	1/1987	Fernandez	
4,659,976 A	4/1987	Johanson	
4,743,831 A	5/1988	Young	
4,876,632 A	10/1989	Ostehout et al.	
4,962,347 A	10/1990	Burroughs et al.	
5,032,825 A	7/1991	Kuznicki	
5,105,130 A	4/1992	Barker et al.	
5,122,427 A *	6/1992	Flowers et al.	429/97
5,248,929 A	9/1993	Burke	
5,293,156 A	3/1994	Shoji et al.	
5,519,383 A	5/1996	De La Rosa	
D388,060 S *	12/1997	Tanaka et al.	D13/103
5,751,217 A	5/1998	Kchao et al.	
5,844,401 A	12/1998	Lee	
5,966,079 A	10/1999	Tanguay	

FIG. 2 is a top view of the power tool battery shown in FIG. 1.

FIG. 3 is a bottom view of the power tool battery shown in FIG. 1.

FIG. 4 is a front view of the power tool battery shown in FIG. 1.

FIG. 5 is a rear view of the power tool battery shown in FIG. 1.

FIG. 6 is a right side view of the power tool battery shown in FIG. 1; and,

FIG. 7 is a left side view of the power tool battery shown in FIG. 1.

The broken line showing of the environment is for illustrative purposes only and forms no part of the claimed design. The broken lines which define the boundaries of the claimed design form no part thereof.
